Application January 27, 1956, Serial No. 561,763

2 Claims. (Cl. 120—18)

This invention relates to a pencil, and more particularly to a pencil embodying a relatively large marking element, so that the invention in one form is adapted particularly for making heavy impressions as in the instance of recording bowling scores.

In U. S. Patent No. 2,285,630 patented June 9, 1942 there is disclosed what is referred to as a crayon type pencil embodying an outer casing in the form of a tube and a hollow stem member mounted within the tube. The marking element is mounted within the stem for axial movement relative thereto between retracted and extended positions, and the soft crayon-like marking element is adapted to be advanced from a retracted to an extended position by a short tubular plunger. The tubular plunger includes a plurality of ears thereon adapted to engage threads formed about the inner wall of the outer casing. The pencil of the aforesaid patent further includes a rotatable head or cap adapted to rotate the stem causing the plunger to descend forcing the marking implement outwardly of the pencil casing to an extended position exposing the marking end thereof in position for use. Under the present invention, a substantially simplified connection is afforded between the stem within the casing and the cap of the pencil so that these parts can be readily associated and disassociated and the stem readily rotated within the casing upon rotating the pencil head. The attachment between the pencil casing and the removable head or cap is likewise of simplified construction, enabling the cap to be readily mounted and dismounted. These reductions in operating structure constitute objects of the present invention.

As was mentioned, the pencil of the aforesaid patent embodies a plunger that is adapted when rotated to advance the marking element of the pencil from a retracted to an extended position exposing the marking end thereof outwardly of the pencil casing. Another object of the present invention is to replace the plunger in the construction according to the aforesaid patent with a yieldable U-shaped plunger having but a single follower thereon adapted to engage the thread formed about the inner wall of the casing. Such enables the plunger to act without binding as will be described.

Other and further objects of the present invention will be apparent from the following description and claims and are illustrated in the accompanying drawing which, by way of illustration, shows a preferred embodiment of the present invention and the principles thereof and what we now consider to be the best mode in which we have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is an elevation of the pencil of the present in-

vention having the marking element thereof retracted within the casing;

Fig. 2 is a view similar to Fig. 1, but being broken away in part, and showing the marking implement having the marking end thereof exposed;

Fig. 3 is an elevational view showing the stem or holder for the marking implement and the plunger disposed therein;

Fig. 4 is a detailed sectional view of the upper end 10 of the pencil showing the way in which the cap or head of the pencil is associated with the pencil casing and the stem within the case;

Fig. 5 is a bottom plan view of the removable cap;

Fig. 6 is a sectional view on an enlarged scale taken 15 substantially on the line 6—6 of Fig. 2; and

Fig. 7 is a fragmentary perspective showing the pencil in a stage of assembly.

The pencil 10, Fig. 1, of the present invention comprises an outer cylindrical casing 11 having a rotatable cap 12 removably mounted thereon at the upper end, and the lower end of the casing 11 is tapered slightly at 13. The casing 11 may be made of any preferred material, and among these are the slightly resilient synthetic plastics for a purpose to be mentioned.

25 As shown in Figs. 2 and 4, the upper portion of the casing 11 is formed with an annular groove 15. The cap 12 is hollow as will be observed, and the opening therein is of slightly smaller diameter than the upper end portion 16 of the casing 11 affording an annular edge 30 that is above the groove 15. The cap 12 is formed with a very shallow groove 12G above the lower edge 17 thereof adapted to receive the upper end portion of the casing 11. By constructing the casing 11 and the cap 12 both of somewhat yieldable plastic, the cap 12 can be pressed on to the upper end of the casing 11, the parts yielding to enable this to be accomplished, and then the upper peripheral edge portion at 16 of the casing 11 snaps into the groove 12G of the cap 12 when the cap 12 has been operatively mounted as shown in Fig. 2. This 35 press or force fit is nevertheless one that enables the cap 12 to be easily rotated when operatively mounted, and the cap 12 can be removed by inserting a blade or the like beneath the lower edge 17 of the cap 12 and into the groove 15 to pry the cap off. Such removal of the cap 12 can as well be accomplished by gripping the cap 12 between the thumb and forefinger and applying leverage thereto, and again the yieldable or resilient nature of the casing 11 and cap 12 enables this to be accomplished.

50 Mounted in the elongated axial chamber of the casing 11 is a stem 20, Fig. 3, of relatively thin sheet steel in the form of a stamping. The stem 20 is tubular in nature as will be observed, and this stem is formed with an elongated slot 21 which extends from the upper end to the lower end thereof. The slot 21 at the upper end portion is narrowed at 22, affording a shoulder 21A, and opposite the narrow slot 22 is a like slot 23 which extends but part way downward along the stem 20 from the upper end thereof. Disposed at 90° to the slots 22 and 23 are a pair of ears 24 and 25 that are stamped from solid portions of the stem 20. When the cap 12 is removed from the casing 11 to expose the upper open end of the casing 11, the stem 20 may be disposed within the 55 casing 11 by inserting the same therein from the upper end of the casing 11. When the stem 20 has thus been associated with the casing 11 the ears 24 and 25 repose on the upper end edge of the casing 11 above the groove 15 as shown particularly in Fig. 4. Under this condition, 60 the lower end of the stem 20 projects slightly beyond the lower end of the casing 11 as shown in Figs. 1 and 2. 65 70 The stem 20 is adapted to hold a marking element

which in the present instance is in the form of a marking crayon 25, and preferably the lower end portion of the stem 20 is tapered slightly as shown in Fig. 3 so as to yieldably grip the portion of the marking element 25 that is co-extensive therewith. To enable such tapering of the lower end of the stem 20 to be accomplished, the slot 21 is extended to the lower end of the stem 20 and is narrowed at 26 affording at the same time a shoulder 21B for a purpose to be mentioned hereinbelow. Other slots as 28 and 29 are formed in the lower end portion of the stem 20 so as to extend upwardly from the lower end for a slight distance. The slots thus afforded enable the lower end portion of the stem 20 to be crimped to afford the desired taper. When the stem 20 has been mounted in the casing 11 as above described, the crayon 25 may be easily inserted in the stem 20 from the lower end thereof.

When the pencil is not in use, the marking element 25 is preferably withdrawn fully inwardly of the casing 11 to protect the marking end thereof, and when it is desired to extend or lower the crayon 25 for recording purposes the stem 20 is rotated by the cap 12 as will be described presently and this causes a plunger within the stem 20 to descend relative to the casing 11 forcing the marking element outwardly.

To enable the stem 20 thus to be rotated by rotating the cap 12, the cap 12 at the interior thereof is provided with a web or blade 32, Figs. 2, 4 and 5, adapted to fit into the slots 22 and 23 in the upper end of the stem 20. Thus, after the stem 20 has been initially mounted in the casing 11 as above described so that the ears 24 and 25 repose on the upper end of the casing 11 the cap 12 is held in one hand and is turned so that the blade 32 thereof can be aligned with the slots 22 and 23 which are in exposed relation in the upper portion of the stem 20 that extends above the upper end of the casing 11. The cap 12 is then pressed down on the casing 11 until the cap snaps into place as described above, and this associates the stem 20 with the cap 12 so that these will rotate together.

The slot 21 in the widened portion thereof between the shoulders 21A and 21B is adapted to receive a generally U-shaped plunger 35 of spring steel or the like. The plunger 35 has a long leg 36 and a short leg 37, and the free end of the short leg 37 is formed with a dog or follower 40 projecting outwardly at substantially right angles relative to the short leg 37. The legs of the plunger 35 are of less width than the widened portion of the slot 21 between the shoulders 21A and 21B, so that the plunger 35 may be disposed within the stem 20 merely by dropping the plunger 35 through the widened portion of the slot 21. The plunger 35 is arranged within the stem 20 so that the free end of the long leg 36 is disposed upwardly, that is, the bight or lower portion 35B of the plunger 35 is adapted to engage the upper end of the marking element 25 as shown particularly in Fig. 2.

The follower 40 on the plunger 35, as shown in Fig. 2, is adapted to ride in a thread 45 formed about the inner wall of the casing 11. As shown in Fig. 2, the thread 45 extends from the upper end of the casing 11 and terminates approximately where the lower end portion of the casing 11 commences to taper.

In assembling the parts of the pencil, one way in which this is accomplished is to first drop the plunger 35 through the slot 21 of the stem 20, and in this connection it may be pointed out that an ear 46, Fig. 3, at the upper end of the stem 20 is pressed inwardly from a solid portion thereof. This ear 46 lies equi-distantly between the ears 24 and 25 and is located somewhat therebelow. The ear 46 serves as a stop for the upper end of the leg 36 of the plunger 35.

After the plunger 35 has thus been associated with the stem 20, the crayon 25 may then be inserted from the

lower end of the stem and the stem 20 is then inserted in the casing 11 from the upper end thereof as described above until the dog or follower 40 reposes on the end of the casing 11 thereby limiting insertion of the stem 20. The stem 20 is then rotated until the follower 40 is aligned with the upper end of the thread 45 as will be apparent from Fig. 5. The dog 40 is then engaged as by the thumb nail and pressed inwardly to engage the thread 45, whereupon further insertion of the stem 20 into the casing 11 is attained by the rotating the stem 20 until the ears 24 and 25 repose on the upper end of the casing 11. The cap 12 is then snapped into place.

To extend the crayon of the pencil after thus being assembled, it is merely necessary to turn the cap 12 in the proper direction to rotate accordingly the stem 20. The stem 20 of course during rotation carries with it the plunger 35, and the follower 40 thereof will descend on the thread 45 causing the bight portion 35B of the plunger to press on the upper end of the marking element 25 forcing the marking element out through the lower end of the stem 20 to an exposed position whereas the marking end thereof is disposed in position for use. Descent of the plunger is limited by the shoulder 21B which catches the dog 40.

After use of the pencil, the head 12 is then rotated to withdraw the plunger 35 sufficiently to enable the lower end of the marking element to be pressed upwardly into the stem 20 into a fully recessed or retracted position.

Of particular importance in the present instant is the spring nature of the plunger 35. Thus, in molding the casing 11 from plastic or like material it is essential that the casing 11 be provided with draft between the opposite ends thereof as is well known in plastic molding, particularly in view of the internal thread 45. However, the diameter dimensional difference in the casing 11 between the upper and lower ends thereof is taken into account by the spring nature of the plunger 35, since the dog or follower 40 is free to compensate between high and low portions. Additionally, there is no binding of the plunger 35 upon withdrawing the plunger 35 entirely to the upper end of the stem 20 where the upper end of the leg 36 engages the ear 46. Any further rotation of the cap 12 in an attempt to further withdraw or retract the plunger 35 at this time is merely manifest in the follower 40 slipping into and out of the thread 45 in what may be termed a free indexing movement.

Another advantage to the particular embodiment is the ease or facility with which the pencil may be assembled. Thus, as was described, the marking element 25 and the plunger 35 is first arranged in the stem 20, the stem 20 then inserted in the casing 11 so that the follower 40 of the plunger 35 is aligned with the thread 45, and the cap 12 then snapped into place. In disassembling the pencil 10, the cap 12 is first removed, and the exposed end of the stem 20 is then grasped between the thumb and forefinger and then rotated to withdraw the plunger 35 upwardly to free the follower 40 of the thread 45, whereupon the stem 20 is then free to be withdrawn from the casing 11.

Hence, while we have illustrated and described the preferred embodiment of our invention, it is to be understood that this is capable of variation and modification, and we therefore do not wish to be limited to the precise details set forth, but desire to avail ourselves of such changes and alterations as fall within the purview of the following claims.

We claim:

1. In a pencil of the kind described having an extendable marking element, a tubular casing having an internal thread extending from the upper end thereof toward the lower end, a tubular stem rotatably mounted within the casing and having a substantially constant internal diameter approximately equal to the diameter

of the marking element and adapted for insertion into the casing from the upper end thereof, said stem having an elongated longitudinal slot therein, a U-shaped resilient plunger adapted to be inserted in said tubular stem through the slot in abutting relation with the marking element and including a follower member projecting through the slot to engage the thread and to prevent rotational movement of the plunger relative to the stem, whereby rotation of the stem with respect to the casing may cause the plunger to move longitudinally through the stem and force the marking element to an extended position of use, and a removable cap for retaining the stem within the casing, said cap having a peripheral tongue-and-groove engagement with the casing to afford a means for mounting of said cap on the upper end of the casing by a force fit and permit free rotational movement of said cap with respect to said casing, said cap further having a transverse tongue-and-groove engagement with said stem to prevent rotational movement of the stem with respect to the cap.

2. In a pencil of the kind described having an extendable marking element, a tubular plastic casing having an internal thread molded therein extending from the upper end thereof toward the lower end, a tubular stem rotatably mounted within the casing and having a substantially constant internal diameter approximately equal to the diameter of the marking element and adapted for insertion into the casing from the upper end thereof, said stem having an elongated longitudinal slot therein and

further having at least one projection extending therefrom into engagement with the upper rim of the casing, a U-shaped resilient plunger adapted to be inserted in said tubular stem through the slot in abutting relation with the marking element and including a follower member projecting through the slot to engage the thread and to prevent rotational movement of the plunger relative to the stem, whereby rotation of the stem with respect to the casing may cause the plunger to move longitudinally through the stem and force the marking element to an extended position of use, and a removable cap for retaining the stem within the casing, said cap being fabricated from a resilient plastic material and having a peripheral tongue-and-groove engagement with the casing to afford a means for mounting of said cap on the upper end of the casing by a force fit and permit free rotational movement of said cap with respect to said casing, said cap further having a transverse tongue-and-groove engagement with said stem to prevent rotational movement of the stem with respect to the cap.
